UNITED STATES PATENT OFFICE.

CHARLEY McDONNER, OF WAUSAUKEE, WISCONSIN, ASSIGNOR OF ONE-HALF TO FRANK E. CHRIST, OF SAME PLACE.

DESIGN FOR A SAW-BLADE.

SPECIFICATION forming part of Design No. 31,362, dated August 8, 1899.

Application filed June 30, 1899. Serial No. 722,469. Term of patent 14 years.

To all whom it may concern:

Be it known that I, CHARLEY McDONNER, a citizen of the United States, residing at Wausaukeee, in the county of Marinette and State of Wisconsin, have invented and produced a new and original Design for a Saw-Blade, of which the following is a specification.

This invention relates to a new and original design for a saw-blade; and it has for its object to provide a design of this character that shall be both useful and ornamental.

The leading feature of the design resides in a saw-blade body having at the working edge thereof alternating pairs of cutting-teeth and raker-shanks, the cutting-teeth of each pair being of a triangular shape, with a V-shaped notch therebetween, and each cutting-tooth having upon one side thereof a rounded convexed face sloping to its inclined edges, and each of said raker-shanks being provided with a pair of outwardly-divergent approximately semicrescent teeth having their contiguous edges merged on a sigmoidal line and their bills curved toward the adjacent cutting-teeth, the notches between the cutting-teeth and also between the latter and the raker-shanks being of the same depth and of greater depth than the U-shaped notch between the teeth of each raker-shank.

The minor features of the design are the saw-blade body having the bases of all the notches rounded and the triangular cutting-teeth being flat upon the side opposite the convexed faces and also provided with rounded apices.

In the drawings, Figure 1 is a side elevation of a crosscut-saw blade embodying the design contemplated by the present invention. Fig. 2 is an edge view of the blade.

Referring to the accompanying drawings, the numeral 1 designates a crosscut-saw blade provided along the working edge thereof with alternating pairs of cutting-teeth 2 and raker-

shanks 3. The cutting-teeth 2 of each pair are duplicates of each other in size and shape and are of the triangular configuration, with a V-shaped notch 3 therebetween, said notch being rounded at its base, as indicated by the reference-numeral 4. Each of said cutting-teeth is provided with a flat face 5 upon one side and upon the directly opposite side with a rounded convexed face 6, sloping to the inclined edges of the tooth, and the latter is further provided with a rounded apex 7. The rounded convexed faces of the adjacent cutting-teeth of each pair are arranged, respectively, in reverse relation, as plainly shown in Fig. 2 of the drawings.

The raker-shanks 3, which alternate with the pairs of cutting-teeth 2, are each provided with a pair of outwardly-divergent approximately semicrescent teeth 8, whose contiguous edges 9 merge together on a sigmoidal line, thereby providing each shank with a U-shaped notch 10 between the teeth thereof. The bills of the divergent raker-teeth 8 are curved toward the adjacent cutting-teeth, and the said U-shaped notches 10 are of less depth than the notches between the cutting-teeth and also between the latter and the raker-shanks, all of which latter notches are of equal depth. The notches between the cutting-teeth and the adjacent raker-shanks are also rounded at their bases, as indicated by the reference-numeral 11.

What is claimed is—

The design for a saw-blade herein shown and described.

In testimony that I claim the foregoing as my own I have hereto affixed my signature in the presence of two witnesses.

CHARLEY McDONNER.
